UNITED STATES PATENT OFFICE.

JOHN S. BAKER, OF EVANSVILLE, WISCONSIN.

WINDMILL.

1,251,619.

Specification of Letters Patent.

Patented Jan. 1, 1918.

Application filed June 30, 1916. Serial No. 106,908.

To all whom it may concern:

Be it known that I, JOHN S. BAKER, a citizen of the United States, residing at Evansville, in the county of Rock and State 5 of Wisconsin, have invented certain new and useful Improvements in Windmills; and I do hereby declare the following to be a full, clear, and exact description of the invention, such as will enable others skilled in the art to 10 which it appertains to make and use the same.

This invention is an improvement in windmills, particularly of the type known as vaneless windmills.

15 In previous constructions of windmills known to me, when the wheel is turning slowly, the bottom sections drop slightly out of the wind and the top sections come back into the wind. This movement of the sections during the rotation of the wheel wears the joints and makes a disagreeable noise which increases with time as the parts become worn.

In overcoming this objection, the invention 20 employs means, such as stop devices which limit the movement of the sections into the wind whereby it is possible to bring each section into engagement with a stop device when moved in one direction. Stop devices are also employed to limit the movement of the sections out of the wind, or in the opposite direction. Should the shipper rod fail in a storm, the construction of the device is such that the wind will hold the 25 sections to which the rod is connected in a safe position, that is, against a stop device with the sails endwise to the wind. Otherwise, the wheel section would continue to turn until it presented its full surface to the 30 wind, which would probably result in injury to the wheel.

Furthermore, in overcoming the objectionable noise, as well as the wear on the parts or joints, means are provided to prevent the 45 dropping of the sections when the mill wheel is rotating slowly, and tension devices are employed which coöperate with such means to prevent the dropping of the sections. The force of the tension devices is sufficient to 50 counteract the force of gravity until a ro-

tating speed has been reached which causes a centrifugal force to act upon the sections and overcome the force of gravity. By the employment of the tension devices, the invention aims to balance the running of the 55 wheel so that the wheel will run at practically constant speed when the wind is sufficiently strong to rotate at a predetermined speed, or in a stronger wind.

Other objects and advantages of the invention will become apparent from the following detailed description thereof taken in connection with the accompanying drawings and the appended claims.

While a preferred embodiment of the invention is disclosed in the accompanying drawings, it is to be understood that the construction therein shown is for the purposes of illustration only, and not as defining the 65 limits of the invention.

In the drawings:

Figure 1 is a detail view, partly in section, of a tower and a part of a wind wheel mounted thereon.

Fig. 2 is a fragmentary view disclosing 75 a spider and its connections with parts of the wheel.

Figs. 3, 4, 5 and 6 are detail views of the stop devices carried by the section journals.

The tower may be of any preferred form 80 or construction. The tower is indicated at 1 and is shown provided with an upper bearing surface 2 near its upper end, and with an annular bearing surface 3 below the upper end of the tower. Rotatably mounted 85 at the upper end of the tower is a shaft supporting device which may be in the form of a casting indicated at 4 having a depending tubular section 5. This tubular section 5 has an annular flanged portion 6 which rests 90 against the bearing 2 of the tower. The tubular portion 5 may be provided with a collar or extended portion 7 to engage the bearing 3 of the tower and limit the upward movement of the tubular portion 5. The 95 usual pitman is indicated at 8 and is provided with a head 9 at its upper end, swiveled in a bearing at 10, which bearing is mounted on a rocking guide 11. The rocking guide 11 is mounted upon an arm 12 of the casting 100

4 and this guide also supports a short pitman 13 which is connected to a crank 14 of the main shaft 15 carried by the casting 4. The casting 4 may have suitable bearings indicated at 16 for the shaft 15, and the shaft may be of a length to extend beyond the casting at each end thereof, as illustrated in the drawings.

The casting 4 is shown provided with an 10 aperture 17 which may be at an angle to the bearing section of the casting 4 which supports the shaft 15. Adjacent the aperture 17 the casting may be provided with a chamber or recessed portion 18 in which may be 15 mounted a sheave 19.

The tower 1 also supports means which may be manually operated for controlling the position of the wheel sections of the mill, the means comprising a rod or wire 20 which 20 may be secured to any suitable means at the base of the tower, such as a lever (not shown), while the upper end of this rod or wire 20 is shown secured to a flattened plate 21 which extends through guide members 22 of the tower and is provided with an arm 23 having a recessed portion 24. This recessed portion is adapted to receive and support a sleeve 25 having a hub 26 which is adapted to be maintained in the 30 recessed portion 24 of the arm 23 by any suitable means which will permit the sleeve 25 and the hub 26 to have rotative movement relative to the supporting arm 23, and which will permit the plate 21 to have reciprocating movement in its bearings 22 to produce a reciprocating movement also of the sleeve 25. This sleeve 25 is shown provided with a rod 27 which extends to a flexible connection shown in the form of a chain 35 40 which passes over the sheave 19 to a rod 29 and operates to transfer the vertical reciprocating movement of the rod 20 and plate 21 to a substantially horizontal movement through the rod 29 by instrumentalities which effect the various movements of the wheel sections.

Mounted on the extension of the casting 4 and preferably splined or otherwise secured to the shaft 15, is a hub 30 for the wheel, 50 the hub being shown provided with a bowl 31 near one end and with an outwardly flared sleeve-like portion 31^a at the rear of the hub. The main portion 30 of the hub is shown provided with a shoulder 32 which 55 may abut against the end 33 of the casting 4 to limit the movement of the hub in one direction. The hub may be provided with flanged members 35 exteriorly thereof to which may be secured the spokes 36 of the 60 wheel. The spokes may be braced by suitable brace rods 37 which are secured to the spokes at 38 and at 39 to the sleeve-like portion 31 of the hub. Slidably mounted upon the tubular arm 34 of the casting 4 is a

sleeve 40 which may be prevented from rotative movement on the arm 34 by any suitable means such as a spline 41. This sleeve 40 is shown provided with an annular flange 42 which serves as means to support a collar 43 and retain the collar in rotative position around the sleeve 40 and the arm 34, by means of the channeled flange 44 of the collar receiving the flange 42 of the sleeve. The collar 43 may be provided also with ears 45 to which may be connected rods 46 75 extending from the collar 43 to an arm 47 of a lever 48.

Two of these levers 48 are shown in the drawings, and they may be pivoted at 49 to the shaft 15 near the end of said shaft. The 80 levers 48 are preferably provided with a plurality of gear teeth 50.

At the end of the shaft 15 opposite to that which contains the crank 14, the shaft may be reduced in diameter to provide a 85 shoulder for the reception of a hub 51 of the shipper spider, the spider being shown provided with a plurality of segments 52. The spider is provided with a plurality of gear teeth 53 on one surface thereof, which 90 teeth are designed to mesh with the teeth 50 of the levers 48. To make sure that the teeth 50 of the sector gear levers will mesh properly with the teeth 53 of the shipper spider, there is provided a fat tooth 54 on 95 the shipper spider which engages a corresponding wide notch 55 on the lever between two of the teeth 50.

Extending from the segments 52 of the shipper lever are a plurality of shipper rods 100 56. These rods 56 are connected to wing-supporting bars 57, said bars being arranged to support a series of wings 58 for the wheel. The shipper rods 56 are preferably pivotally connected at 59 directly to a bar 60 carried 105 by the wing-supporting bars 57. At the end of each spoke 36 there may be provided terminal mounting elements 61 which have bearing ears 62 to support hinge rods 63. These hinge rods extend from one spoke 36 110 to an adjacent spoke 36 and serve as means for pivotally mounting castings 64 which are secured to the wing-supporting bars 57. These castings 64 are each shown provided with an elongated arm 65 serving as a stop 115 when the casting 64 is moved on the rod 63 in one direction, so that said arm 65 will engage a portion 66 of the terminal element 61. This permits the wings 58 to be positioned at substantially right angles to the 120 spoke 36. When it is desired to position the wings 58 in substantial alignment with the spoke 36, or at substantially 90 degrees from the position which the wings assume when the supporting arm 65 engages the element 61, other stop devices are employed to limit such movement of the wing-supporting bars 125 and the wings around the rod 63. This may

be effected by having the stop device in the form of a nib 67 carried by the casting 64 engage a rearwardly extended portion 68 of the terminal element 61.

- 5 The spokes 36 may be provided also with a plate 69 to which may be secured a tension device 70 shown in the form of a coiled spring from which spring extends a rod 71 which is pivotally connected with sectors of 10 the shipper spider. Two of the devices are shown in the drawings, but it is obvious that any number of these springs may be employed to effect the function desired.

When the wheel sections are opened out 15 of the wind, the arms 65 of the casting 64 bear against the spoke terminals 61. They are held in this position by the tension of the wire or rod 20 which is connected to the manually controlled means which operate 20 plate 21. It is to be understood that the force applied to this wire 20 is communicated through plate 21 to the sleeve 25 and from the sleeve to the rod 27 through the flexible connection, shown as a chain 28 to 25 the rod 29 which is connected with the slide- able sleeve 40 to move the sleeve toward the larger end of the hub sleeve 31. The re- ciprocation of the sleeve 40 acts through its collar 43 and rods 46 to move the levers 48 upon their pivots 49 and thereby rotate the 30 shipper spider 51 by reason of the teeth 50 of the levers 48 engaging the teeth 53 of the spider. This rotation of the shipper spider extends the springs 70 and at the same time 35 operates upon the shipper rods 56 to turn the wheel sections 57 so that their sail surfaces are parallel to the wind direction. When the wire 20 to the manually controlled lever is released, the springs 70 operate to ro- 40 tate the shipper spider and draw upon the shipper rods 56 to thereby bring the sail surfaces at right angles to the wind. It will be understood that the sail surfaces are prevented from traveling more than flat into 45 the wind by the stops 67, 68 on the castings 64 and 61, respectively.

The center of gravity of the sail surfaces when they are flat in the wind is preferably a little toward the tower and toward the 50 center of the wheel from the hinged rod 63. Hence, as the wheel rotates, centrifugal force draws upon the shipper rods 56 and this force, when it becomes great enough, will cause the extension of the springs 70. 55 The position the sections assume is such a position that there is a balance between the centrifugal force of the sections and the springs 70, and the proportioning of the lever arms and spring properties is such that 60 the wheel will run at practically constant speed whenever the wind is sufficiently strong to bring it up to a predetermined speed.

Should one of the shipper rods 56 become

disengaged at either end, its section will be 65 thrown by centrifugal force and wind pressure to a position parallel to the wind, but cannot go further because of the stops 65 engaging a portion 66 of the spoke terminal.

The advantage of the stops 67 and 68 70 which prevent the sections from coming more than flat into the wind is that they re- 75 duce wear of the sections on the rod 63. Were it not for these stops, when the wheel is rotating slowly, the sections at the bot- 75 tom of the wheel would drop slightly out of the wind and take up whatever looseness of motion there would be in the various joints permitting this motion, and when on the top of the wheel, the sections would 80 drop to a position flat to the wind, taking up the slack motion in the opposite direc- 85 tion. This dropping causes a disagreeable noise in windmills of the vaneless type and an unnecessary wear on the joints, which increases their looseness and noise. The ad- 90 dition of these stops prevents the dropping of the sections as the force of the springs 70 through the shipper rods 56 is more than sufficient to counteract the force of gravity 90 until a rotating speed has been reached which causes a centrifugal force in excess of the force of gravity.

The tubular sleeve 31^a serves as a protec- 95 tion against weather for the slideable sleeve 40, and the bowl 31 serves to protect the piv- 100 oted levers 48 from sleet and ice.

It is obvious that various changes in the form and proportion of parts may be made without departing from the spirit of the in- 100 vention, and the right is reserved to make such changes and alterations as fairly fall within the scope of the appended claims.

Having thus described my invention, what I claim is:

1. A windmill including a shipper spider having gear teeth, levers mounted near the spider and having geared segments to mesh with the teeth of the spider, and manually controlled instrumentalities to move the 110 geared levers to rotate the shipper spider.

2. A windmill including a wheel having a plurality of movable sections, a shipper spider having means of connection with the wheel sections, gear levers to rotate the 115 shipper spider to move the sections of the wheel into and out of the wind, and resilient means carried by the wheel and having means of connection directly with the ship- 120 per spider to exert force to maintain the wheel sections in one position and to oppose the centrifugal force of the sections and gear levers.

3. A windmill comprising a shaft, a casing therefor, a wheel having a tubular hub and a plurality of movable sail sections carried by the hub, a shipper spider mounted on the shaft and having means of connection with 125

the sail sections, a sleeve slidably mounted on the shaft casing and housed by the tubular hub, a swivel rotatably mounted on the sleeve, gear members to rotate the shipper spider relative to the shaft by movement of the sleeve and manually controlled means to reciprocate the sleeve for moving the wheel sail sections to a predetermined position.

4. A wind-mill comprising a tower having a casting pivotally mounted thereon to receive a wheel shaft, a wheel provided with a plurality of movable sections mounted on said shaft, a spider carried by the shaft, means of connection between the spider and the movable sections, coöperating gear members carried by the shaft and spider, a sleeve slidably mounted upon the casting and connected with said gear members, and manually operated means carried by the tower to shift the sleeve upon the casting to thereby rotate the spider relative to the shaft, said rotation operating to move the sections of the wheel.

5. A windmill comprising a shaft having a wheel mounted thereon, said wheel being provided with pivotally mounted sections, means to limit the pivotal movement of the sections in a plurality of directions, a casing for the shaft, a shipper spider carried by the shaft and rotatable independently of the movement of the shaft, means to connect the spider with the wheel sections, said spider having a plurality of gear teeth, a plurality of levers having gear teeth to mesh with the teeth of the spider for rotating the spider and moving the wheel sections, a sleeve slidably mounted on the shaft casing and having means of connection with the gear levers, and manually controlled means to reciprocate the sleeve for moving the wheel sections to a plurality of positions.

6. A windmill comprising a shaft having a wheel mounted thereon, said wheel being provided with a hub and pivotally mounted sections, means to limit the pivotal movement of the sections in a plurality of directions, a shipper spider rotatable on the shaft, means to connect the spider with the wheel sections, resilient means carried by the wheel to maintain the spider and wheel sections in a predetermined position, a plurality of levers pivotally mounted on the shaft, said levers having gear teeth to mesh with gear teeth on the shipper spider, a casing to house the shaft, a sleeve housed by the wheel hub and slidably on the shaft casing, means to connect the sleeve with the gear levers, and manually controlled means to reciprocate the sleeve for moving the wheel sections to a plurality of positions.

7. A windmill comprising a shaft, a casing therefor, a wheel mounted on the shaft and having a plurality of movable sections, a shipper spider rotatable on the shaft and

having means of connection with said sections, a plurality of levers pivoted to the shaft for rotation therewith, said levers having gear segments to mesh with a toothed surface of the shipper spider, said spider having a plurality of fat teeth adapted to mesh with a corresponding wider space of each lever gear segment to insure proper meshing of the teeth, and manually controlled instrumentalities to move said levers and shift the wheel sections to a plurality of positions.

8. A windmill comprising a tower having a swiveled top and a tubular member extending into the tower through which a pitman operates, the swiveled tower carrying a wheel with movable wings, and instrumentalities to move the wings including segmental gear levers and a reciprocating sleeve, an elongated plate mounted in guideways in the tower and adapted to be reciprocated by manually controlled means, said plate having an arm to mount a tubular sleeve which encircles the pitman and is capable of rotative movement with relation to the tower and the elongated plate, and flexible means to connect the tubular sleeve to the reciprocating plate, whereby the reciprocation of the elongated plate will operate the reciprocating sleeve of the swiveled top to move the wings of the wheel.

9. In a wind mill, the combination of a wheel provided with movable sections, stops and journals therefor, a shipper spider, and gear members to rotate the spider.

10. In a wind mill, the combination of a wheel provided with a plurality of movable sections, section journal stops, a shipper spider to move the sections, and lever segment gears to rotate the spider.

11. In a wind mill, a wheel comprising a plurality of movable sections, a toothed spider to move the sections and toothed levers to move the spider.

12. A windmill having a wheel provided with a plurality of movable sections, a shipper spider therefor, sector gears for controlling the movement of said sections, said gears operating to rotate the spider relative to the wheel, and spring actuated devices for limiting the movement of said sections.

13. A wind mill having a wheel provided with a plurality of movable sections, a hub for the wheel, connecting means between the hub and the sections, and gear members within the hub to move the sections.

14. A windmill provided with a wheel comprising a plurality of movable sections, mounted upon a hub provided with a shield, a shipper spider, and pivotal elements mounted within the shield of the hub to cooperate with the spider to move the sections.

15. A wind mill comprising a tower, a casting rotatably mounted thereon, a shaft mounted in said casting, a wheel mounted on the shaft, a sleeve slidable upon the casting within the hub of the wheel, a plurality of movable sections carried by the wheel, a shipper spider carried by the shaft, means to connect said spider to the wheel sections, and segmental gears operated by the sleeve to rotate the spider to move the 10 sections.

In testimony whereof I affix my signature in presence of two witnesses.

JOHN S. BAKER.
